ATTORNEY

Patented Sept. 27, 1927.

UNITED STATES PATENT OFFICE.

ROBERT S. NORTHMORE, OF CHICAGO, ILLINOIS, ASSIGNOR TO THE LOUDEN MACHINERY COMPANY, OF FAIRFIELD, IOWA, A CORPORATION OF IOWA.

HANGER FOR OVERHEAD TRACKWAYS.

Application filed March 16, 1927. Serial No. 175,712.

My invention relates to supporting hangers for trackways used for overhead carrying, and it consists of an improvement in the construction of the parts whereby the lengths of the hangers may be more accurately adjusted, and by this means the trackway may be more accurately adjusted in the positions in which it will be held at different points below the overhead supports, as may be required in the adjustment of the trackway.

In the accompanying drawings, forming a part of this specification, Fig. 1 is a side elevation of a hanger embodying my invention, with a short section of a trackway B connected to its lower end. Fig. 2 is a vertical transverse section on line 2—2 of Fig. 1, the lower central portion of the line being slightly deflected. Fig. 3 is a horizontally disposed transverse section on line 3—3 of Fig. 1, the central portion of the line being also slightly deflected. Fig. 4 is a detail view.

Referring to the drawings, A represents the main body of the hanger which is composed of two mating members made of metal, the upper edge of a track rail, such as that shown by B being clamped between the mating members, preferably by a bolt C, the lower ends of the members being grooved to catch over and hold a bead D on the track rail B. The members A are fitted on the upper portions of their inner sides with a pair of vertically disposed grooves E, as most plainly shown in Fig. 3. These grooved portions are provided with a series of spaced apart holes or recesses F, the purpose of which will be presently explained.

An inverted U shaped member G, which may be called an open ended link having a head H on each open end, and which may also be called the overhead connecting member, is inserted in the grooves with its heads H in certain of the holes or recesses F, as may be required for the adjustment of the track-rail B in its proper position below its overhead support. The closed end of the link will be connected to the overhead support in any suitable manner, well known to those skilled in the art, which is therefore not shown. The upper ends of the members A are held together preferably by a finger I on the upper end of one of the

members which is inserted in an adjacent 55 hole J in the other member.

To assemble the parts, the open ends of the link G are first placed in the grooves of the member A having the hole J, with its heads H in the proper holes or recesses 60 F, and the horizontal groove in the lower end of the member is then placed over one side of the bead D. The finger I of the other member A is then placed in the hole J and the lower end of that member is then 65 closed down so its horizontal groove will catch over the other side of the bead D, and thus hold the track rail B between them. After this the bolt C is placed in position and the members A are thus 70 clamped in position on the headed ends of the link G and also on the bead D of the track rail B.

I make no claim to the hanger as above described, as my invention resides in the 75 novel manner of arranging the heads H on the link G and the novel arrangement of the holes or recesses F in the members A. Heretofore these holes or recesses on the opposite sides of the members A have been 80 placed in the same horizontal plane to each other, and the headed ends of the link G have been made of equal lengths so the heads H would be in the same horizontal plane to correspond with the holes or recesses F. When made in this way the only 85 adjustment of the hanger that could be made was to move the heads of the link from the holes or recesses they were occupying to the holes or recesses immediately 90 above or below them.

My invention consists in staggering the holes or recesses in the members A so the holes or recesses on one side of the members 95 will occupy a horizontal position intermediate of the position of the holes or recesses on the other side, and then making the headed ends of the link G of unequal lengths to correspond with the positions of these holes or recesses. By this means, adjustments one half less can be made than if the corresponding heads and holes or recesses occupied the same horizontal plane. All that is necessary is to turn the link 100 around so that in lengthening the hanger the long headed end of the link will occupy the hole or recess occupied by the short headed end, and in shortening the hanger 105

to turn the link around so the short headed end of the link will occupy the hole or recess before occupied by the long headed end.

My invention is the essence of simplicity and it reduces the adjustment of the hanger to one half of what could be heretofore done with the prior construction. I have continued throughout the description to use the alternative terms holes or recesses on account of the different materials of which the member A may be made. When made of sheet metal and stamped into shape holes have to be punched through the sheets to furnish supports for the heads H, but when made of malleable iron recesses in the inner sides of the members A will be sufficient and need not be extended through to form holes as shown in the drawing.

What I claim and desire to secure by Letters Patent is—

1. In hangers for overhead trackways having a pair of mating clamping members adapted at their lower ends to be connected to and hold in position a trackway, and their upper portions being adapted to adjustably clamp and hold a member to be connected to an overhead support, the upper portions of said clamping members being provided on their inner faces with a pair of vertically disposed series of recesses, and

the overhead connecting member being provided with a pair of headed ends adapted to be inserted in any of the corresponding recesses, to adjust the length of the hanger, said headed ends and the corresponding recesses of the series on one side being set in horizontal planes half way between the recesses in the opposite side, whereby adjustments of half the vertical distance between the recesses may be made by turning the headed ends of the connecting member from one side to the other.

2. In hangers for overhead trackways having a pair of mating clamping members adapted at their lower ends to be connected to and hold in position a trackway, and their upper portions being provided with a pair of vertically disposed series of holes or recesses adapted to receive and hold between them a pair of headed ends of an open ended connecting link, whereby the length of the hanger may be adjusted to hold the trackway in higher or lower positions, said headed ends and the corresponding holes or recesses of one series being set in horizontal planes half way between the holes or recesses of the other series, as and for the purpose set forth.

ROBERT S. NORTHMORE.
